UNITED STATES PATENT OFFICE.

CORNELIUS F. SULLIVAN, OF BOSTON, MASSACHUSETTS.

DIE FOR MAKING SCREW-DRIVER BLADES.

SPECIFICATION forming part of Letters Patent No. 562,934, dated June 30, 1896.

Application filed October 6, 1894. Serial No. 525,083. (No model.)

To all whom it may concern:

Be it known that I, CORNELIUS F. SULLIVAN, a citizen of the United States, residing at Boston, in the county of Suffolk and State of Massachusetts, have invented certain new and useful Improvements in Dies for Making Screw-Driver Blades, of which the following, taken in connection with the accompanying drawings, is a specification.

10 My invention relates to certain improvements in dies for manufacturing screw-driver blades, whereby I am enabled to form screw-driver blades from wire or metal bars, as hereinafter fully described, and pointed out in the claims.

15 Referring to the accompanying drawings, Figure 1 represents a side view of the upper holder and dies embodying my invention. Fig. 2 is a similar view of the lower holder and dies. Fig. 3 is a plan or view of the under side of the upper holder and dies. Fig. 4 is a plan or top view of the lower holder and dies. Fig. 5 is a vertical cross-section taken on line xx of Fig. 4. Fig. 6 is a vertical cross-section taken on line yy of Fig. 4. Fig. 7 is a view of a piece of wire or metal bar cut to the required length to form a screw-driver blade. Fig. 8 is a view of the same reduced or pointed at one end and chamfered at the 20 other end ready to be operated upon by the dies. Fig. 9 is a view of the same after being operated upon by the dies and pressed into shape. Fig. 10 is a cross-section taken on line zz of Fig. 9.

25 A represents the upper die-holder; A' , the head for securing the same in the press.

B is the lower die-holder, which is secured to a bed-plate by bolts passing through holes b .

30 At one end of each of the die-holders A B is secured a die C, the surfaces $a' b'$ of which are beveled off at opposite angles, so that when they come in contact with the wire or metal bar they will press it and form point of the screw-driver blade. The lower die is made 35 with a projecting piece c , that forms one end of a gage for the wire or metal bar and also prevents its spreading lengthwise when compressed. Each of the dies is formed with a tailpiece C' , having a slot d therein, and are 40 each secured to its die-holder by a single bolt D, said bolt passing through the slot and into a screw-threaded hole e in the holder. The

holders are grooved out, as shown, (see Figs. 5 and 6,) so that the dies cannot twist therein. Two or more of said holes e are made in the 55 holders, so that the position of the screw D can be changed to adjust the die according to the length of the screw-driver blade to be made. At the other end of the holders A B are secured dies E to form a small flange on 60 each side of the end of the screw-driver blade for holding it in the handle and prevent its turning in the same. These dies are made with a half-round depression f , which is somewhat smaller in diameter than that of the 65 wire or metal bar, so that the dies will press out a portion of the wire and form a flange g on each side. (See Figs. 9 and 10.) These dies are made with tailpieces E' and are secured to the holders by bolts D in the same 70 manner as described with reference to the dies C.

In the central portion of the lower die-holder B is secured a holder for the wire or metal bar to be operated upon. This holder 75 consists of a block of metal H, secured to one side of the die-holder by a bolt H' , and is made in its center with a slot h , the bottom of which is somewhat lower than the face of the dies C E, so that when the wire or metal 80 bar is dropped in it will rest at each end upon said dies, but be held longitudinally by said holder H.

J is a gage secured to one side of the lower die-holder B and held in place by a screw J' , 85 passing through a slot in the tail j of said gage, so that it can be adjusted as required. The upper end of this gage passes above the top of the die-holder B, the space between the inner edge of this gage and the projecting 90 piece c on the die C being just sufficient to admit the length of wire or metal bar to be operated upon.

The operation is as follows: The wire or metal bar K is first cut to the required length. 95 (See Fig. 7.) It is then reduced or pointed at one end, as shown at k , and chamfered off at its other end, as shown at k' . (See Fig. 8.) It is then placed in the holder H, which retains it longitudinally, and the gages J and c 100 retain it so that its ends rest upon the dies C E in their proper position. The upper dies are then brought down and the point k is pressed into the form shown in Fig. 9, and at

its other end are pressed the flanges *g g*, as shown in Figs. 9 and 10. The object of these flanges is to prevent the tool turning in its handle, and by means of the chamfered end 5 *k'* the tool can be forced into a handle having a hole somewhat smaller in diameter than the wire or metal bar itself.

What I claim is—

1. The die-holders *A, B*, in combination with the dies *C, C*, having beveled contact-surfaces *a', b'* the lower die having a projecting piece *c*, said dies being adjustably held to the die-holders, and the adjustable gage *J*, substantially as and for the purposes set forth.
- 15 2. The die-holders *A, B*, in combination

with the dies *C, C*, having beveled contact-surfaces *a', b'*, the dies *E, E*, having circular recesses *f, f*, said dies being adjustably held to the die-holders the adjustable gage *J*, and the wire-holder *H*, all arranged and operating substantially as and for the purposes set forth.

In testimony whereof I have signed my name to this specification, in the presence of two subscribing witnesses, on this 13th day of September, A. D. 1894.

CORNELIUS F. SULLIVAN.
